UNITED STATES PATENT OFFICE.

EDWARD C. MEIER, OF PHOENIXVILLE, PENNSYLVANIA.

BOILER.

1,263,586.

Specification of Letters Patent. Patented Apr. 23, 1918.

Application filed May 10, 1917. Serial No. 167,840½.

To all whom it may concern:

Be it known that I, EDWARD C. MEIER, a citizen of the United States, residing at Phoenixville, in the county of Chester and State of Pennsylvania, have invented certain new and useful Improvements in Boilers, of which the following is a specification.

My invention consists of improvements in 10 boilers. One object of my invention is to make a boiler which will be of simple construction and efficient in action.

Another object is to so design my improved 15 boiler that all of the parts will be readily accessible for cleaning purposes.

Another object is to so construct my improved boiler that a preheater for the feed water will be provided and to so design the preheating portion that it will permit the 20 incoming feed water to readily absorb heat and thus greatly add to the efficiency of the boiler.

A further object of my invention is to so 25 construct the boiler casing that the walls will be arranged vertically and horizontally and to so shape the casing that an indentation will be produced in the outer surface of the wall to provide a convenient place for the location of the smoke flue.

These objects, and other advantageous 30 ends which will be described hereinafter, I attain in the following manner, reference being had to the accompanying drawings in which—

Figure 1 is a sectional elevation of my improved boiler.

Fig. 2 is a sectional elevation, substantially similar to Fig. 1, showing a modification in the form of feed water preheater.

Fig. 3 is a section on the line 3—3 of Fig. 40 1, and

Fig. 4 is a fragmentary rear elevation of the lower drum construction of the preheater.

Referring to Figs. 1 and 3, 1 represents the 45 boiler casing having vertical front, rear, and side walls, the rear wall 2 having an off-set or stepped portion 3 which connects with the upper vertical portion 4 of said rear wall, the off-set portion being substantially horizontal and forming an indentation 5 in the rear wall.

An outlet passage for the products of combustion, is illustrated at 6, and a damper 7 is provided to regulate the amount of opening through said outlet passage, it being

noted that a flue (not illustrated) can connect with said outlet passage and fit within the space provided by the indentation 5.

Two boiler units 8 and 9 are arranged 60 within the casing 1, the boiler unit 8 comprising a plurality of water tubes 10 connecting at their top and bottom with drums 11 and 12. The boiler unit 9 includes a plurality of tubes 13 which connect at their 65 top and bottom with drums 14 and 15.

The drums 11 and 14 are connected by 70 tubes 16, and the drums 12 and 13 are connected by tubes 17, it being noted that the tops of the drums 11 and 14 are also connected by a tube 18 which acts as an equalizing tube between the steam spaces of the drums 11 and 14.

The drum 14 has a main steam pipe 19 leading therefrom, and the drums 12 and 75 15 have blow-off pipes 20 and 21 connecting therewith. The drums 11, 12, 14, and 15, are arranged horizontally and supported within the side walls, the drum 12 being further supported by a pedestal 22 on the 80 bottom of the casing.

The drums 11 and 12 are in different vertical planes so that the tubes 10 extend at an incline toward the front wall 23 of the casing. This is also true of the drums 14 85 and 15 so that the tubes 13 also extend at an incline and substantially parallel with the tubes 10 of the boiler unit 8.

A grate 24 is provided adjacent the front 90 wall 23 and at the bottom of the casing thus producing a fire box 25 which is located forward of the boiler unit 8. A baffle 26 is provided between the tubes 10 and extends upwardly from the drum 12 throughout a portion of the length of said latter 95 tubes, stopping short of the drum 11 so as to provide a passage 27 for the products of combustion rising from the fire box 25.

A baffle 28, extending between the oppositely disposed side walls of the casing 1, 100 is located between the tubes of the boiler units 8 and 9. This baffle is arranged as illustrated substantially on a level with the top of the baffle 26 and consists of fire bricks 29 which rest on angle bars 30. These 105 angle bars are connected with a plate 31 and form a rigid supporting structure for the bricks 29. Furthermore, the bricks being located above and forward of the angle bars and plate, receive the direct heat of the 110 products of combustion passing through the passage 27 and thus protect said angles and

plate against the direct heat of the products of combustion which pass downwardly to the rear of the baffle 26 as will hereinafter be more fully described.

5 A second baffle 32 is located between the boiler units 8 and 9 and is of the same construction as above described in connection with the baffle 28, only that it is arranged at a lower level.

10 Another baffle 33 is arranged between the tubes 13 of the boiler unit 9 and extends downwardly from the drum 14. This baffle is supported at its lower end by an angle bar 34, this angle bar resting upon clamps 15, the latter being adjustably secured to the tubes 13 of the boiler unit 9.

The lower end of the baffle 33 stops short of the drum 15, and thus provides a passage 36 between it and said drum. The top of

20 the baffle 32 is arranged as illustrated, substantially on the level with the bottom of the baffle 33.

With this arrangement of the baffles 26, 25, 32, and 33, the products of combustion from the fire box 25 are compelled to pass upwardly between the tubes which are forward of the baffle 26, thence through the passage 27 whereby the drums 11 and 14, upper portions of the tubes 10, and the 30 upper portions of the tubes 13, which are forward of the baffle 33, are heated. Then they pass downwardly between the baffles 26 and 33 and in so doing are split up or divided by the baffles 28 and 32 causing 35 them to pass between the rear tubes of the boiler unit 8 and the forward tubes of the boiler unit 9. Part of said products of combustion then pass between the baffles 26 and 32 and serve to heat the drum 12, thence 40 move rearwardly and combine with the portion of the products passing between the baffle 32 and the baffle 33, then all of said products of combustion combine and pass through the passage 36 and upwardly to the 45 rear of the baffle 33 and finally pass out through the outlet passage 6 to the flue.

I preferably form cleaning doors 35^a and 36^a in the side walls of the casing and arrange these doors above the baffles 28 and 50 32, so that any dirt collecting on the latter can be removed therefrom by a rake inserted through said doors.

A comparatively small drum 37 is located on the top of the boiler casing 1 55 and has a water inlet valve 38 connecting therewith. The drum 37 is connected to another small drum 39 by straight pipes 40, said pipes extending through the casing 1 and into the interior thereof to the rear of 60 the tubes 13 of the boiler unit 9.

The drums 37 have openings 41 and 42 respectively, which are in direct alinement with the straight pipes 40. These openings 41 and 42 are closed by plugs 43 and 44 65 during the operation of the boiler. Short

pipes 45 connect the drum 39 with the drum 15. These pipes 45 are fewer in number than are the pipes 40 as clearly shown in Fig. 2, so that the water entering the valve 38, thence through the pipes 40 and into the drum 39, is retarded and caused to move slowly through the pipes 40, thus the feed water by being retarded is caused to absorb considerable heat within the casing prior to entering the drum 15. 75

In the construction illustrated in Fig. 1, it will be noted that the drum 39 is partially embedded within the rear wall 2 of the casing and the opening 42 and plug 44 are located outside of said rear wall. This arrangement of the drums 37 and 39, and the pipes 40, permits the ready cleaning through the openings 41 and 42 from the outside of the boiler casing.

By having the pipes 45 and 40 of the same 85 diameter, and also by employing a less number of pipes 45 than pipes 40, the combined cross sectional area of the interior of the pipes 45 is less than the combined cross sectional area of the interior of the pipes 40 90 and this is what causes a slow movement of the feed water within the pipes 40 and permits it to remain in the pipes 40 for a greater length of time than if the combined area of the pipes 45 was similar to the combined area of the pipes 40, it being understood that the pipes 44 are sufficient to supply the boiler unit with all the water that it needs during the operation of the boiler. The fact that the water moves slowly 100 through the long pipes 40 permits it to be heated to a high temperature before it enters the boiler proper, thus adding to the efficiency of the boiler.

In the form of my invention shown in 105 Figs. 2 and 4, the construction is substantially identical as that described in connection with Figs. 1 and 3 with the exception that instead of having the lower feed water drum embedded within the wall of the 110 boiler, and having the plug on the outside of the casing, the lower drum, as illustrated at 46 in Fig. 2, is entirely within the boiler casing and to permit access to the opening and plug within said boiler 46, I provide a 115 passage 47 in the rear wall of the boiler casing, said passage being normally closed by a door 48.

In this construction, the pipes 49, which correspond with the pipes 45 of Fig. 1, are 120 of greater length than said pipes 45. In all other respects the elements shown in Figs. 2 and 4 are similar to those described in connection with Figs. 1 and 3, and I have therefore given similar parts corresponding reference numerals. 125

It will thus be noted that by the above described construction, a boiler is provided in which the hot products of combustion efficiently heat the several tubes, drums, and 130

- pipes, and the arrangement of the baffling and water preheating elements is such as to cause the absorption of the heat in an extremely efficient manner.
- 5 Furthermore, it will be noted that the construction is such that it is easy for a man to get in the boiler casing and within the several chambers provided in order to efficiently clean the several parts.
- 10 While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.
- Having thus described my invention, what 20 I claim as new and desire to secure by Letters Patent is:
1. The combination in a boiler, of a casing, a boiler unit mounted within the casing, two feed water drums arranged respectively at the top and bottom of the casing, said bottom drum having openings outside of the wall of the casing, the other of said drums having openings located outside of the top of said casing, pipes connecting said
- drums and extending through the space 30 within the casing, means for admitting feed water to one of said drums, means forming communication between the other of said drums and the boiler unit, said openings being in alinement with said pipes, and means 35 for closing said openings, substantially as described.
2. The combination in a boiler, of a casing, a boiler unit mounted in the casing, two feed water drums arranged respectively 40 adjacent the top and bottom of the casing, pipes connecting said drums within the casing, means for admitting water to the top one of said drums, means forming communication between the bottom one of said drums and the boiler unit, each of said drums having a portion extending outside of said casing, said latter portions having openings therein in alinement with said 45 pipes, and means for closing said openings, substantially as described.
- In testimony whereof I have signed my name to this specification in the presence of two subscribing witnesses.
- EDWARD C. MEIER.
